BLIND STRUCTURE

Nicholas L. Etten, Cedar Falls, Iowa

Application March 14, 1951, Serial No. 215,469

4 Claims. (Cl. 160—34)

1

This invention relates to improvements in a blind structure, and more particularly to a blind structure of the permanent or semi-permanent type mountable over a window or other opening on the outside of a building, or which can be built in flush with the wall of the building incorporated during the erection of the building, and which blind is adjustable in a vertical direction, although the invention may have other uses and purposes as will be apparent to one skilled in the art.

In the past, many and various types of blind structures or sunshades of the so-called permanent type have been developed for mounting over a window or other opening on the external side of a building. Most of that type of a blind is made of sheet metal or equivalent material. In every instance of which I am aware, formerly known blinds of the permanent type have extended out over the upper portion of the window at an angle defined by the use of allochiral end panels of triangular shape supporting a suitable canopy. In some cases, such blinds were adjustable or foldable, only from the outside of the building, and at no time did they completely cover the window or other opening, if it were desired to do so. Further, they were not adjustable to a desired extent in a vertical direction over all or a portion of the window, could not be used in a manner eliminating the need of any blind on the inside of the window if desired, projected an objectionable distance outwardly from the building, were not in keeping in most cases with the architecture of the building necessitating a frequent sacrifice of external appearance in order to benefit by an exterior blind, were not as universal in character as desired, and were objectionably expensive both in original cost and upkeep.

With the foregoing in mind, it is an important object of the instant invention to provide a blind occupying a minimum space and projecting to a minimum extent from a building, the blind structure being of such character that regardless of adjustment of the blind, the distance of projection from the building never varies.

Another object of this invention is the provision of a blind for disposition on the external side of a window or other building opening, which is of the permanent type, and which is so constructed as to eliminate the need of any blind or equivalent on the inside of the window, if the user so desires.

It is also an object of this invention to provide a blind structure for disposition on the external side of a building over a window or other opening,

2

which is fully adjustable over all or part of the window, in a vertical direction.

Another feature of this invention resides in the provision of a blind structure so arranged that it may be adjusted to completely enclose a window over the outside thereof in the event the occupants leave the building for a period of time.

It is also a feature of the invention to provide a blind structure mountable over the outside of a window or other building opening, which is vertically adjustable to cover any desired amount of the window, which permits vision from the interior outwardly, prohibits ordinary exterior vision through the window into the interior, and yet provides adequate ventilation.

Another desideratum of this invention is the provision of a blind structure mountable over the outside of a window or other building opening, which structure includes a plurality of spaced slats extending transversely across the window opening, which slats are movable bodily in a vertical direction.

Also a desideratum is the provision of a blind structure of the character set forth in the preceding paragraph, wherein the slats slope outwardly and downwardly, and the angle with the horizontal of each slat increases as the slat moves downwardly.

Still a further object of the invention resides in the provision of a blind structure wherein a plurality of spaced transversely extending slats are carried by corresponding lazy-tong assemblies at each end of the slats, such assemblies being concealed by the frame of the blind structure.

It is also an object of the invention to provide a blind structure embodying corresponding lazy-tong assemblies at opposite sides of the frame, with spaced transversely extending slats attached to links of the assembly, or with the ends of the slats forming links of the respective assemblies.

While some of the more salient features, characteristics and advantages of the instant invention have been above pointed out, others will become apparent from the following disclosures, taken in conjunction with the accompanying drawings, in which—

Figure 1 is a pictorial illustration of a blind structure embodying principles of the instant invention mounted over a window of a building, and showing the blind in fully closed position;

Figure 2 is also a pictorial view similar in character to Fig. 1, but showing the blind in partially open position;

Figure 3 is an enlarged fragmentary vertical cross sectional view of the upper portion of the

blind structure taken substantially as indicated by the line III—III of Fig. 1, looking in the direction of the arrows;

Figure 4 is a fragmentary vertical sectional view similar in character to Fig. 3, but taken through the lower portion of the blind structure, as indicated by the line IV—IV of Fig. 1;

Figure 5 is a diagrammatic view illustrating the cord arrangement by which adjustment of the blind slats is obtained;

Figure 6 is a fragmentary plan sectional view, with parts shown in elevation, taken substantially as indicated by the line VI—VI of Fig. 3;

Figure 7 is also a fragmentary plan sectional view, with parts shown in elevation, taken substantially as indicated by the line VII—VII of Fig. 4;

Figure 8 is a fragmentary vertical sectional view through the upper portion of a blind structure, this figure being similar in character to Fig. 3, but showing a somewhat different form of construction; and

Figure 9 is a view similar in general character to Fig. 4, but showing the lower portion of the blind structure of Fig. 8.

As shown on the drawings:

In the first illustrated embodiment of the instant invention, seen in Figs. 1 to 7 inclusive, and with particular reference to Figs. 1 and 2, there is shown a blind structure embodying a box-like frame 1 which may be made of any suitable material, such as sheet metal. This frame is provided with opposed narrow border panels 2—2 at the front thereof, which are preferably only of sufficient width as to conceal the actuating mechanism of the blind. At the top thereof, the open front frame is provided with a valance 3 extending downwardly a sufficient extent to conceal all of the internal blind structure when the same is adjusted to fully open position. As seen best in Figs. 3 and 7, the sides of the frame, including the border panels 2—2, are somewhat channel-like in shape, the rear flange thereof being supported by a vertically extending angle iron 4, one flange of which is secured to the frame and the other flange of which may be secured to the building wall 5 by means of screws 6 or equivalent fastening means. With reference now to Fig. 2, it will be seen that, if desired, side braces 7 of any suitable construction may be employed.

With reference again to Fig. 2, it will be noted that the entire frame structure of the blind may be mounted to the building wall 5 around the frame of a window 8, and the frame does not project an objectionable distance from the wall of the building. At this point it should be noted that since the entire blind structure is contained within the frame 1, this frame could be incorporated inside the building wall so that the outer portion of the frame would be flush with the outside wall of the building if done during erection of the building. Likewise, the frame 1 might be embodied in an interior partition of the building, with or without a window in the partition, so that the blind structure might be utilized to effect a temporary closure of a doorway or the like through such partition.

The blind mechanism is identical in construction, except for the allochiral characteristics of certain parts, at each side of the frame 1. With reference now to Figs. 3, 4, 6 and 7, it will be seen that the structure at one side of the frame embodies a channel-like track 9 riveted or equivalently secured to the sides of the frame 1 as indicated at 10 and bolted or equivalently secured to

the respective border panel 2 as indicated at 11. This track, of course, is rigid. A lazy-tong assembly extends vertically along the side of the frame 1, and this assembly embodies an anchoring link 12 having its upper end anchored by a pivot pin 13 extending through the upper part of the track and the adjacent side of the frame as seen clearly in Figs. 3 and 6. As is usual with a lazy-tong assembly, a series of parallel links 14 are pivotally connected to another series of parallel links 15 in a manner to form a succession of connected X's. Thus, one of the links 15 will have an upper terminal pivot connection 16 to the lower end of a link 14, is centrally pivoted to another link 14 as at 17, and has a terminal pivot 18 at its lower end with the upper end of still a third link 14. Connected to the shaft of each terminal pivot 18, or only to a part of them if so desired, is a roller 19 which rides within the aforesaid channel track 9 as seen clearly in Figs. 3, 4 and 7. These rollers being locked in the channel tracks insure a straight up and down movement of the lazy-tong assembly and maintain that assembly in fixed location relatively to the frame, except for the vertical adjustability of the assembly.

Now with reference to Figs. 3 and 4, it will be seen that with the exception of the several uppermost links 15 which are always behind the valance 3, these links 15 carry transverse slats 20 which are substantially box-like in shape in that they have forward, rear, and end flanges. These slats are preferably made of thin sheet metal. The slats 20 may be attached to the links 15, or if so desired, the end flanges of these slats may form the links 15, depending upon which may be more economical and feasible with a particular production system. Being associated with the links 15, the slats 20 slope outwardly and downwardly, and the angle of these slats with the horizontal increases as the slats move downwardly by virtue of the lazy-tong assembly mountings for the slats. Thus, when the slats are in fully lowered position as seen in Fig. 1, the window is completely enclosed so as to preclude ordinary external vision through the window, permit some vision from the interior out, and provide adequate ventilation by virtue of the fact that the spacing between the slats is never completely closed.

A simple arrangement for adjusting the slats upwardly or downwardly is indicated diagrammatically in Fig. 5, wherein a cord 21 has one end secured as at 22 to the lowermost foreshortened link 14. The cord then extends upwardly over a pulley 23, downwardly to form an elongated loop 24, thence upwardly over a pulley 25, across the entire upper part of the frame, and over a pulley 26 at the opposite side of the frame, or the right hand side, as viewed in Fig. 1, from which pulley the cord depends and is secured to the terminal slat 14 on the other side of the frame. It will be noted, therefore, that it is a simple expedient to pull on the loop 24, holding both reaches of the cord, and the blind will be elevated. It is a simple expedient to anchor the blind in a desired position of elevation by merely winding the loop 24 about a cleat 27 mounted on the inside of the blind frame next the window. When it is desired to lower the blind, the loop 24 is released from the cleat, and the blind permitted to drop by gravity to the desired extent.

It will be noted that the entire blind structure projects only a minimum extent from the

wall of the building, or not at all if incorporated in that wall. The blind may be simply adjusted to obscure the window to any desired extent. If the occupants leave the building for a period of time, the blind may be lowered to its full extent and thus effect a complete closure of the window. It will also be apparent that the entire structure including the slats and the frame may be decorated with any desirable color or color combinations. The entire structure embodies simple stampings, simple securing means, may be very economically manufactured and is extremely durable.

In Figs. 8 and 9 I have shown a modified form of structure wherein a frame 1a is utilized which must of necessity employ wider end rails, that is the frame projects farther from the building than the frame 1 above described. This frame 1a is provided with the same valance 3 and interiorly with the same channel track 9 as above described. Lazy-tong assemblies are provided at each side of the frame, but in this instance these assemblies include an elongated anchoring link 12a, a series of parallel links 14 and a series of elongated parallel links 15a. The parallel links 15a are associated with the links 14 by terminal pivots 16, intermediate pivots 17, and another pivot 28 which is terminal in character insofar as the link 14 is concerned, but is substantially centrally of the elongated links 15a, which project well forward of the pivot point 28. The lower and forward ends of the links 15a carry rollers 29 to ride the track 9. Slats 30, of the same general character as the above described slats 20, are secured to the projecting portions of the links 15a as indicated at 31 by bolts or in an equivalent manner. The arrangement of the adjusting cord 21 is substantially of the same character as previously described, with the exception that the end of the cord is associated with the intermediate part of the lowermost link 15a as indicated at 32 in Fig. 9.

The blind structure shown in Figs. 8 and 9 functions in the same manner as that above described in connection with Figs. 1 to 7 inclusive, and is desirable where added space is desired between the window or other opening and the blind. With the exception of additional space occupied, and a slight increase in the cost of manufacture, the modified structure of Figs. 8 and 9 possesses all the advantages of the first described embodiment.

It will be understood that modifications and

variations may be effected without departing from the scope of the novel concepts of the present invention.

I claim as my invention:

- 5 1. In a blind, a frame for disposition around a window, a lazy-tong assembly on each side of said frame for vertical movement, alternate links of said assemblies projecting beyond their terminal pivots at one side of each assembly, and transverse slats carried by the projecting portions of said alternate links.
- 10 2. In a blind, a frame for disposition around a window, a lazy-tong assembly on each side of said frame for vertical movement, alternate links of said assemblies extending forwardly and downwardly beyond their outer terminal pivots, and transverse slats carried by the extending portions of said alternate links.
- 15 3. In a blind, a frame for disposition around a window, a lazy-tong assembly on each side of said frame for vertical movement, alternate links of said assemblies extending forwardly and downwardly beyond their outer terminal pivots, transverse slats carried by the extending portions of said alternate links, a vertical track at the outer part of each side of said frame, and rollers to ride said tracks mounted on said extending links adjacent the outer corners of said slats.
- 20 4. In a blind, an open-front box-like frame for disposition around a window opening, an inwardly opening channel track in each side of said frame, a lazy-tong assembly at each side of said frame, a series of rollers carried by each assembly to ride said tracks, an inturned flange on each track to
- 25 35 lock the respective rollers therein, vertically spaced slats connected to said assemblies, and border panels on said frame concealing said assemblies and the ends of said slats.

NICHOLAS L. ETTEN.
